LOOM BOX MOTION LEVER

Victor H. Jennings, Worcester, Mass., assignor to
Crompton & Knowles Loom Works, Worcester,
Mass., a corporation of Massachusetts

Application May 1, 1943, Serial No. 435,330

8 Claims. (Cl. 139—181)

This invention relates to improvements in the shuttle box operating mechanisms for looms and it is the general object of the invention to provide an improved lever so constructed as to hold its adjustments accurately.

Shuttle box operating mechanisms for looms ordinarily comprise an actuator controlled by a pattern mechanism, a lifter directly connected to the shuttle boxes, and a force transmitting mechanism between the actuator and lifter. In certain types of shuttle box mechanism the force transmitter takes the form of a lever one end of which is attached to the actuator and the other end of which is connected to the lifter. The shuttle boxes have floors which must align accurately with the shuttle race of the lay for proper picking and boxing conditions of the shuttle as the boxes shift, and in order that the amount of the shifts may correspond to the distances between the floors it is customary to provide an adjustment in the lever.

As heretofore made the levers have included the bearing finger slidably radially on the lever and held in adjusted position by a set screw on the lever. In order to hold the finger in position it is usual to set the screw against the finger tightly enough to produce depressions of sufficient width to interfere with subsequent fine adjustments. It is an important object of my present invention to retain the general form of lever heretofore used but construct it in such a way that the finger can be given fine adjustments with respect to the lever by means other than the customary holding set screw so that previous depressions made by the set screw will not interfere with the adjustments.

In one form of shuttle box operating mechanism which has gone into general use the finger of the lever is directly connected to a vibrator lever and the finger has a flat shank to fit into a narrow slot in one of the lever arms extending radially from the lever axis. It is another object of my present invention to bevel the end of the shank adjacent to the lever axis and combine it with a saddle slotted to receive the beveled finger end and adjustable laterally of the shank for the purpose of varying the distance of the shank from the lever axis.

With these and other objects in view which will appear as the description proceeds, my invention resides in the combination and arrangement of parts hereinafter described and set forth.

In the accompanying drawing, wherein a convenient embodiment of my invention is set forth,

Fig. 1 is a rear elevation of part of a loom

having shuttle box mechanism equipped with my present invention,

Fig. 2 is an enlarged rear elevation of the lever shown in Fig. 1 with the shank relatively close to the lever axis,

Fig. 3 is an end elevation of the lever shown in Fig. 2, parts being in section, and

Fig. 4 is a view similar to a portion of Fig. 2 but with the finger held in a position farther from the lever axis than that shown in Fig. 2.

Referring particularly to Fig. 1, I have shown a loom frame 10 having a lay 11 on which are mounted shifting shuttle boxes 12 mounted on the upper end of box lifter rod 13. The latter is connected in the usual manner to a box lifting chain 14 which extends upwardly toward the box operating mechanism. In the present instance the latter mechanism is the well-known Knowles head K having a vibrator lever 15 carrying a vibrator gear 16 attached to a connector 17. The vibrator gear 16 is shiftable vertically between upper and lower mutilated constantly rotating cylinders 18 and 19 by pattern mechanism 20 for the purpose of moving the connector 17 either to the right or left as viewed in Fig. 1.

The loom frame supports a stationary stud 25 on which is mounted a force transmitting lever 26 having a lower arm 27 operatively connected to the box lifter chain and having an upper arm 28. The latter arm is provided with a narrow slot 29 to receive a finger 30 provided with a gudgeon 31 which affords pivotal connection for the right end of the connector 17, as shown in Fig. 1. Finger 30 has a flat narrow shank 32 fitting into slot 29 and held in place by set screw 33. As the connector moves back and forth the lever 26 rocks on stud 25 to cause vertical motion of the shuttle boxes.

The matter thus far described is of common construction but sets forth only one form of the lever 26. For further understanding of similar mechanisms, and also as illustrating other forms of the lever 26, reference may be had to prior Patents Nos. 551,104 and 787,448. Because of the different forms which the lever can take as indicated by the prior art I do not wish necessarily to be limited to the particular shape set forth herein.

In carrying my present invention into effect I provide means by which the finger 30 can be held in any one of a plurality of finely adjusted positions at different distances from the stud 25. Referring particularly to Figs. 2 and 3, it will be seen that the right side of the shank 32 is forced against the wall 37 of slot 29 by the screw 33.

The lever arm 28 is provided with a transverse preferably rectangular opening 40 having a flat bottom 41, side walls 42, and a top 43 through which the shank 32 extends into the opening 40. The lower end of the shank is inclined or beveled as at 45 relatively to the bottom edge 41 of the opening 40 and rests on a similarly beveled edge 46 of a saddle 47 having spaced parallel walls 48 and 49 extending above the inclined surface 46 and defining a slot 50 which receives the bottom beveled end of the shank.

A positioning screw 52 is threaded into the lever arm 28 opposite the opening 40 and preferably relatively low in the latter so that it engages that part of the saddle below the slot 50. The positioning screw 52 can be turned to be extended into or moved out of the opening 40 and its adjusted position can be held by a lock nut 53.

In operation, it may be assumed that the initial setting of the finger is desired to be relatively near the stud 25, in which case the positioning screw 52 will be moved to the left as viewed in Fig. 2 to permit the saddle to occupy a position to the left of the center of opening 40. The finger shank is then pressed down firmly against the saddle to cause close engagement between the surfaces 45 and 46 while the saddle is limited as to left hand movement as seen in Fig. 2 by the positioning screw 52. After the parts are thus adjusted the screw 33 is tightened and the gudgeon 31 will be held in relatively low position to receive the connector 17.

When the top of gudgeon 31 wears due to use, the connector moves toward stud 25 and the angular motion of lever 26 is increased beyond its proper movement. To compensate for this change the set screw 33 is loosened, the lock nut 53 released, and the positioning screw 52 turned in a direction to feed it into the opening 40 and thereby cause right hand movement of the saddle 47. The effect of this lateral movement of the saddle is to cause upward movement of the finger by cooperation of the surfaces 45 and 46. When the finger has been raised to the desired position lock nut 53 is tightened and screw 33 set to hold the finger in its new adjusted position with gudgeon 31 high enough to cause correct angular movement of lever 26.

The saddle walls 48 and 49 engage the sides of the lower end of the shank 32 and hold the saddle in proper vertical position in the slot for opening 40 and also prevent the saddle from moving laterally out of opening 40. The bottom surface 54 of the saddle slides along and lies on the surface 41 of the opening 40, thereby limiting down motion of the saddle and shank relatively to arm 28. Because of the fact that the vertical position of the finger is determined by the saddle and the positioning screw 52, it is not necessary to tighten the set screw 33 to the extent heretofore necessary and the previously experienced pitting or notching of the narrow left edge of the shank 36 is avoided.

From the foregoing it will be seen that I have provided simple means by which the finger can be adjusted readily on the arm 28 with respect to the lever axis by means of a saddle having an inclined surface to engage a similarly inclined surface on the bottom of the shank 32. It will further be seen that the vertical adjustment of the finger is effected by movement of screw 52 and maintained by the saddle, for which reason it is not necessary to set the screw 33 as tightly as heretofore.

Having thus described my invention it will be seen that changes and modifications may be made therein by those skilled in the art without departing from the spirit and scope of the invention and I do not wish to be limited to the details herein disclosed, but what I claim is:

1. In a box lever for a loom having an actuator, a lever arm provided with a transverse surface, a finger mounted for movement along said arm toward and from the lever axis and having on one end a gudgeon for said actuator, and wedge means between said surface on the arm and the other end of said finger which by lateral movement relatively to said arm and finger effects movement of the latter along said arm to move said gudgeon relatively to the lever axis.
2. In a box lever form a loom having an actuator, a lever arm provided with a transverse surface, a finger mounted for movement along said arm toward and from the lever axis and having on one end a gudgeon for said actuator, wedge means between said surface on the arm and the other end of said finger, and means on the lever to move said wedge means along said surface and cause said wedge means to effect movement of the finger along said arm to change the distance between said gudgeon and the lever axis.
3. In a box lever for a loom having an actuator, an arm provided with a narrow slot extending therethrough toward and from the lever axis and communicating with a transverse opening extending through said arm, a finger having a gudgeon on one end for said actuator and having the other end extending through said narrow slot and into said transverse opening, and finger setting means in said transverse opening to effect movement of said finger in said narrow slot, said setting means having surfaces inclined to each other, one of said surfaces engaging said finger and another of said surfaces engaging said arm.
4. In a box motion lever for a loom having an actuator, an arm forming part of the lever, a finger mounted on said arm for movement toward and from the lever axis and having at one end thereof a gudgeon for said actuator, a saddle engaging opposite sides of the finger and having oblique surfaces one engaging a part of the arm and the other engaging said finger, and means to move said saddle laterally of said arm and finger to effect movement of the latter on said arm to change the position of said gudgeon with respect to the lever axis.
5. In a box lever for a loom having an actuator, an arm provided with a lateral opening therethrough having a surface extending transversely of the arm, a finger movable along said arm toward and from the lever axis and having a gudgeon for the actuator on one end thereof and having the other end extending into said opening, a saddle in said opening engaging opposite sides of the finger and having oblique surfaces one engaging said finger and the other engaging said surface of the opening, and means to move the saddle laterally of said finger and arm to effect movement of the finger relatively to the arm to vary the distance between the gudgeon and lever axis.
6. In a box lever for a loom having an actuator, an arm provided with a narrow slot extending toward and from the lever axis, a thin finger having opposite flat surfaces and extending through said narrow slot and having on one end a gudgeon for the actuator and movable in said slot toward and from the axis thereof, a saddle

having spaced walls engaging said flat surfaces, and means to move the saddle on the lever laterally of the finger and parallel to said flat surfaces, said saddle having two surfaces oblique with respect to each other one of which is located between said walls and engages the finger and the other of which is slid able along said arm.

7. In a shuttle box lever for a loom having an actuator, an arm forming part of said lever, a finger member provided with a gudgeon for said actuator and mounted for movement on said arm toward and from the lever axis, a positioner member 10 slideable transversely on said arm and engaging said finger member, and setting means on the arm to move said positioner member transversely on said arm, one of said members having a surface inclined to the direction in which the positioner member is moved by said setting means and engaging the other member, whereby lateral movement of the positioner member 15 relatively to the finger member effects move- 20

ment of the latter relatively to the arm to vary the distance between said gudgeon and the lever axis.

8. In a shuttle box lever for a loom having an actuator, an arm member, a finger member mounted on the arm member for movement therealong toward and from the lever axis and having a gudgeon for said actuator, a positioner for the finger member movable on the arm member transversely thereof, and setting means to move the positioner laterally of said finger member, the arm member and positioner having mutually engaging surfaces extending transversely of the finger member, and the positioner and finger member having engaging surfaces one of which is oblique to the engaging surfaces of the arm member and positioner, so that movement of the positioner by the setting means transversely of the arm effects a change in the distance between the gudgeon and lever axis.
